A. E. GARBER,
GAS ENGINE GAS SAVER AND CARBON DECOMPOSER.
APPLICATION FILED JAN. 22, 1917.

1,325,286.

Patented Dec. 16, 1919.

UNITED STATES PATENT OFFICE.

ARTHUR E. GARBER, OF SAN DIEGO, CALIFORNIA.

GAS-ENGINE GAS-SAVER AND CARBON-DECOMPOSER.

1,325,286.

Specification of Letters Patent.

Patented Dec. 16, 1919.

Application filed January 22, 1917. Serial No. 143,612.

To all whom it may concern:

Be it known that I, ARTHUR E. GARBER, a citizen of the United States, residing at San Diego, in the county of San Diego and 5 State of California, have invented certain new and useful Improvements in Gas-Engine Gas-Savers and Carbon-Decomposers, of which the following is a specification.

My invention relates to an apparatus to 10 be used in connection with gas engines for reducing the quantity of gas consumed and for reducing the carbon in the cylinders. The objects of my invention are: first, to provide a device of this class in which air 15 may be introduced into the manifold and to the engine cylinders when the carbureter is shut off when using the compression of the engine for retarding the vehicle in going down hill; second, to provide a means for introducing varied quantities of 20 water and hot air into the manifold above the carbureter for reducing the carbon therein, adding to the efficiency of the fuel mixture and reducing the quantity of gas 25 consumed; third, to provide means for shutting off the water to the manifold when the carbureter is closed or when desired; fourth, to provide combined automatic means for 30 controlling the flow of hot air and water to the manifold; and fifth, to provide an apparatus of this class which is very simple and economical of construction, durable, easily 35 installed and will not readily get out of order.

With these and other objects in view as 40 will appear hereinafter, my invention consists of certain novel features of construction, combination and arrangement of parts as will be hereinafter described in detail 45 and particularly set forth in the appended claim, reference being had to the accompanying drawings and to the characters of reference thereon which form a part of this specification in which:

Figure 1 is a diagrammatic view of my 45 device complete. Fig. 2 is a side elevational view of my valve mechanism. Fig. 3 is a top or plan view thereof. Fig. 4 is a detailed view of the hand control mechanism. Fig. 5 is a fragmentary side elevational view of the exhaust manifold showing my heating device thereon. Fig. 6 is a transverse sectional view thereof. Fig. 7 is a sectional view of my water feed observation device. Fig. 8 is a front view thereof. Fig. 9 is a sectional view of the water

and air control and mixing device. Fig. 10 is a top or plan view thereof and Fig. 11 is a side elevational view of the valve 2.

Similar characters of reference refer to 60 similar parts throughout the several views.

The valve casing 1, valve 2, hand control 3, heater 4, observation device 5, air inlet and water mixer 6, water supply tank 7 and pipe 8 constitute the principal parts of my 65 apparatus. The valve casing 1 is shaped as shown best in Figs. 2 and 3 of the drawing, provided with an enlarged central portion 1^a adapted for the valve 2 and with extended neck portions 1^b and 1^c. The end 70 1^b is threaded externally upon which is screwed a coupling 8^a adapted for connecting the pipe 8 with the neck portion 1^b of the valve casing. This valve casing is provided with a tapered hole in the center 75 adapted for the valve 2 to fit into and close said hole. Extending each way are holes 1^d and 1^e to the ends of said valve casing the hole 1^d connecting the valve 2 with the pipe 8 and the hole 1^e connecting the valve 80 2 with the nozzle 1^f which is screwed into the end 1^c of the valve casing. This neck 1^c is externally threaded adapted to fit into a threaded hole in the manifold or in some cases into an L as shown in Fig. 1 and the 85 other end of said L is screwed into the manifold above the carbureter. When the L is used as shown in Fig. 1, the nozzle 1^f is screwed into the L which is internally threaded for that purpose. The valve 2 is 90 provided with a hole 2^a conforming to the hole 1^b and on the opposite side said hole widens at 2^b shown best in Fig. 11. Mounted in said casing below the hole 1^e is another hole 1^g which extends from said 95 valve to the outside of said casing so that when the valve 2 is turned in one direction the communication through the casing will be closed, when it is turned in the position shown in Fig. 2 of the drawing there 100 is an open passage through said casing from the pipe 8 to the manifold. When it is turned in the opposite direction the communications through said valve will be closed but the hole 2^b connecting the hole 1^g 105 with the hole 1^e will be open allowing air from the outside to enter the manifold. The valve 2 is operated by means of a lug 2^c to which is connected a rod 3^a which extends to the hand control 3 and it connects 110 with a lever 3^b pivotally mounted on said hand control so that when the lever 3^b is

2

moved the valve 2 is revolved in said casing for opening and closing the valve and for allowing air from the outside to the manifold as desired. This rod 3^a is preferably 5 inclosed in a flexible casing 3^c. To the other end of the pipe 8 is connected the air and water heater 4 which consists of a metallic piece, shaped as shown best in Figs. 5 and 6 and on the inside is provided a 10 corrugated wire netting, 4^b adapted to support the same and prevent its being easily crushed from the outside and also to conduct the heat internally through said heater thus adding to its efficiency. At the other 15 end of said heater is mounted the air intake and water mixer 6. This air intake and water mixer is a cup shaped device provided at its lower end with a neck 6^a threaded externally adapted to screw into the internally 20 threaded lug 4^a on said heater. It is provided on one side with a hole 6^b adapted for a pipe 6^c which communicates with one side of the observation device 5. Mounted in the upper end of this cup 6 is a web shaped 25 frame 6^d, the sides extended downwardly and forming a valve seat 6^e, and mounted centrally therein is cylinder 6^f in which is adapted to reciprocate the valve rod 6^g, upon the lower end of which is secured the 30 valve 6^h. Mounted on the upper end of this cylinder by means of threads is an adjusting nut 6ⁱ and between it and the end of the rod 6^g is a compression spring 6^j which is adapted to keep the valve 6^h seated. 35 Mounted on the dash of the vehicle in sight of the operator is the observation device 5 which is a hollow casing provided with an inlet 5^a and an outlet 5^b. In the side next to the operator it is provided with a glass 40 5^c so that the operator can see whether or not water is dropping from the nozzle 5^d. Communicating with the inlet 5^a and its handle extending out through the front side is provided a needle valve 5^e adapted to 45 close off the water in the upper side of said observation device as desired. From the inlet 5^a is provided a pipe 5^f which communicates with the tank 7 which is mounted in any suitable place inside of the hood of 50 the vehicle.

Though I have shown and described a particular construction, combination and arrangement of parts I do not wish to be limited to this particular construction, combination and arrangement but desire to include in the purview of my invention the construction, combination and arrangement substantially as set forth in the appended claims.

It is obvious that with this construction 60 there is provided an apparatus for automatically providing a regulated quantity of water and air to the manifold above the carburetor, that there is also provided means for allowing the outside air to the manifold 65 when the carburetor and water and hot air valve is closed, that there is provided an efficient means for heating both the air and water from the engine exhaust, that there is provided means for determining the 70 quantity of water going to the manifold and for regulating and stopping the same, that the device is simple and economical of construction, durable, easily installed and will not readily get out of order.

Having thus described my invention what I claim as new and desire to secure by Letters Patent:

In a device of the class described, the combination of a water supply tank, a combined water and air heater, means for conducting water from said water supply tank to said combined water and air heater, means for observing the quantity of water conducted and for regulating and stopping 80 the same, means for automatically admitting air with said water to said combined water and air heater, means for conducting the heated water and air to the manifold of a gas engine, and means in connection with 85 said last mentioned conducting means for shutting off the supply of heated water and air to said manifold and for simultaneously admitting air from the outside to said manifold with the stopping of said heated water 90 and air supply.

In testimony whereof I have hereunto set my hand at San Diego, California, this 15th day of January, 1917.

ARTHUR E. GARBER.
